STEEL BUILDING CONSTRUCTION

George Vincent Palmer, Los Angeles, Calif.

Application August 10, 1939, Serial No. 289,491

2 Claims. (Cl. 108—6)

This invention relates to steel building, and pertains particularly to an eave construction useful in sectional metal roof structures.

The principal object of the invention is to provide an eave construction adapted to provide a weather seal against the intrusion of rain, sand, dust or the like, which the wind might tend to force interiorly of the building structure.

A further and important object of the invention is to provide an eave construction which cooperates with a superficial roof-covering provided for a sectional metal roof construction.

A further object of the invention is to provide a combined roof-covering and an eave construction particularly adapted to sectional metal roof structures embodying the use of prefabricated "hollow-cell" panel members.

The construction of the present invention is intended to be utilized in roof constructions embodying a plurality of preformed metal elements of the "hollow-cell" panel type, in which such elements are arranged in contiguous aligned relationship to define the structural plane of a roof, with the hollow cells opening out at an edge of the roof. In such constructions, unless there is a pronounced pitch to the roof, rain will be carried into the open-ended hollow cells, together with sand or dust, and form moisture-retentive deposits which induce a rusting of the roof material. The presence of these rust-inducing deposits materially lessens the effective life of the roof, and seriously detracts from the so-called "permanence" of steel buildings.

According to the present invention, I arrange a plurality of the hollow-cell panels in the desired relation to form the roof structure, with the open ends of the hollow cells extending to an edge of the roof in the customary manner, and the eave construction may comprise a layer of conventional roofing material superimposed upon the roof surface and brought over the open ends of such cells, together with a facia member secured to the edge of the roof and covering such open cell ends, the roofing material being disposed between the ends of the cells and said facia member and carried back over the face of the facia member to the upper surface of the roof, at which position it is folded back upon itself and sealed in any suitable manner.

The accompanying drawing illustrates an embodiment of the invention, and referring thereto:

Fig. 1 is a sectional detail of a roof structure incorporating the invention, showing an edge portion of a roof formed with hollow-cell build-

ing elements, the view being taken along the longitudinal axis of one of the hollow cells; and

Fig. 2 is a partly broken-away perspective view of the edge of a roof provided with an eave construction according to my invention.

Referring to the drawing, I have shown a roof construction formed of a plurality of sectional metal building elements 1, each provided with hollow-cell stiffening members 2, defined for example by the provision of a flat plate body member 1a and an undulating plate stiffening member 1b intersecured in any suitable manner, as by spot-welding or the like. Superimposed upon the flat upper surface defined by the hollow cells 2 I have provided a layer of heat-insulating material 3, such as that obtainable under the trade name of "Celotex," for example, the layer 3 being secured to the elements 1 through the agency of a plurality of so-called "sheet-metal drivescrews," not shown, by an intermediate layer 3a of mastic adhesive material, or in any other suitable manner.

The roof-covering 4 is applied over the upper surface 5 of the layer 3, being extended over the full span of the roof in successive strips and being suitably adhesively secured thereto as in conventional practice, and is then brought over the open ends of the hollow cells as at 6. Prior to laying the roofing material over the open ends of the cells 2, I install a plurality of nailing plugs within the ends of certain of the hollow cells 2, as at 7, 7a and 7b, these plugs being formed of wood or the like, and being driven into the open ends of the cells so as to be compressively wedged therein, and preferably, but not necessarily, flush with the ends thereof. After the roofing material 4 is brought down over the ends of the cells 2 as at 6, a facia plate 8 is nailed in place over the ends of the cells, the nails being driven into the spaced nailing blocks 7, 7a and 7b, etc., as at 9. The facia plate is preferably carried down somewhat below the bottom edge of the roof structure, as at 10, to provide a drip edge, and to keep rainwater from running back under the eave, particularly when a flat roof is constructed.

The roofing material is then carried forward under the bottom edge 10 of the facia plate 8, as at 11, then carried upwardly over the face of the facia plate as at 12, and laid back over the portion 4 as at 13, a suitable sealing composition such as asphaltum or pitch being applied to the intermediate space 14 to seal the exposed end of the portion 13, as at 15. This layer of sealing composition may be applied by the procedure known

as "hot-mopping," if desired, with good results.

The nailing blocks will be employed at as frequent intervals along the length of the roof as is necessary to hold the fascia in position, as will be apparent to one skilled in the art. It will further be appreciated that the insulating layer 3 may be disposed under the hollow-cell roof construction, or omitted, if desired, without departing from the spirit and contemplation of this invention. I do not choose to be limited to the specific embodiment of the invention herein delineated, but rather to the scope of the subjoined claims.

I claim:

15 1. In a sectional steel building construction embodying a plurality of prefabricated elongated metal building elements arranged in contiguous aligned relationship to form a roof surface and having one or more longitudinally extending stiffening members defining hollow cells opening at their ends at an edge of said roof, a weather-

sealed eave construction for such an edge, which comprises: a fascia plate extending along such edge in covering relation to the open ends of said hollow cells, and secured to said roof; and a layer of roofing material covering the upper surface of 5 said roof and extending between said fascia plate and said edge, along the lower edge of said fascia plate, upwardly along the forward face of said fascia plate, and thence back upon itself at the upper surface of said roof, and secured to itself 10 in overlapping relation adjacent such edge.

2. In a sectional steel building construction, a weather-sealed eave construction as set forth in claim 1, said fascia plate being secured to said roof through the agency of a plurality of plug members compressively wedged within the open ends of spaced hollow cells of said plurality of metal building elements, said fascia plate being mechanically bonded to said plug members at 15 intervals along its length.

GEORGE VINCENT PALMER.
